CLAIM

The ornamental design for a tire, as shown and described.

DESCRIPTION

The patent or application file contains at least one drawing executed in color. Copies of this patent or patent application publication with color drawing(s) will be provided by the Office upon request and payment of the necessary fee.

1. Tire

1.1 : Front

1.2 : Left

1.3 : Perspective

1.4 : Enlarged

The rear view is the same as the front view after being rotated 180 degrees clockwise, so the rear view is omitted; the right view is symmetrical to the left view, so the right view is omitted; the top and bottom views are the same as the front view, so the top and bottom views are omitted; the red box with the indication "A" shown in reproduction 1.1 is an enlarged view of the tire shown in reproduction 1.4.
